(57) **CLAIM**

The ornamental design for an electronics enclosure, as shown and described.

DESCRIPTION

FIG. 1 is a front, top, and right perspective view of an electronics enclosure showing the new design.

FIG. 2 is a rear, bottom and left perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a left-side elevation cross-section view thereof, taken along line 9-9 of FIG. 3; and,

FIG. 10 is a detailed view of FIG. 9.

The broken lines are directed to environment and are for illustrative purposes only; the broken lines form no part of the claimed design.
